UNITED STATES PATENT OFFICE.

CHARLES B. KELLOGG, OF CHICAGO, ILLINOIS, ASSIGNEE OF ONE-HALF TO EUGENE U. KNIGHT, OF CHICAGO, ILLINOIS.

DISPLAY STAND.

1,411,281.

Specification of Letters Patent. Patented Apr. 4, 1922.

Application filed January 12, 1921. Serial No. 436,636.

To all whom it may concern:

Be it known that I, CHARLES B. KELLOGG, a citizen of the United States, residing at Chicago, Illinois, have invented certain new and useful Improvements in Display Stands, of which the following is a specification.

This invention relates to stands for displaying various articles of merchandise for sale, and has among other objects, the following:

To construct out of sheet material a device in such a manner that the amount of material wasted, in proportion to the size of the device, will be reduced to a minimum; to so form a device of the character stated that the blank can be readily folded and assembled to produce with a minimum amount of labor the completed device; to so construct a device of the character stated that the holding members which hold the device in assembled position do not have to be cut out of a portion of the sheet of material which will be visible in the completed article; and such further objects, advantages and capabilities as will later more fully appear.

My invention further resides in the combination, construction and arrangement of parts illustrated in the accompanying drawings, and while I have shown therein a preferred embodiment, I desire the same to be understood as illustrative only and not as limiting my invention.

In the drawings annexed hereto and forming a part hereof, Fig. 1 shows a plan view of the blank after the same has been cut from the sheet of material; Fig. 2 is a perspective view of the display stand which is formed by folding the blank shown in Fig. 1 and locking the parts in assembled relation; Fig. 3 is a vertical section substantially along the plane indicated by the line 3—3 Fig. 4; Fig. 4 is a vertical section substantially along the plane indicated by the line 4—4 Fig. 3; and Fig. 5 is a horizontal section substantially along the plane indicated by the line 5—5 Fig. 3.

In constructing my device a blank is stamped out of a sheet of material such as cardboard, heavy Bristol board or, if desired, thin sheet metal. This stamping is done in a single operation and leaves the blank in shape to be easily formed into final shape by a few simple folding operations.

In most cases it will probably be desired to print upon the sheet material, either before or after the stamping operation, appropriate descriptive or advertising matter. This can easily be done either before or after the stamping operation, but before the folding operation.

In the form shown the body member 1 is provided along one edge with a front section 2, to which are connected side members 3. To the edge of body member 1, opposite that to which the front 2 is connected, is a back member 4, provided with locking arms 5; having at their ends hooks 6, adapted to engage in slots 7 in the outward end of the sides or wings 3. If desired a top 8 of any appropriate form may be left attached to the back 4, this top being utilized for the reception of a picture, descriptive or advertising matter, or for any other desired purpose.

It is preferred to score the blank, during the stamping operation, along the lines 9, 10, 11, and 12 in order to make it more easy to fold the sheet material as desired. Diagonal cuts 13 and 14 are made so that depressions or openings, as desired, may be formed in the body member 1 for the reception of the articles to be displayed. Of course these cuts may be made in other forms or arrangements than those shown if desired, so as to produce the shape and arrangement of depressions or apertures preferred.

One of the important features of this invention is the shape and arrangement of the parts 2, 3, 5, 6 and the position and direction of the folding lines 9, 10 and 11. It was considered desirable that the holding members 5 and 6 should not be cut out of the body member 1, and yet that when the device was assembled it should form a closed figure, that is, that there should be no noticeable apertures between the sides 3, the body 1 and arms 5. It was therefore necessary to cut the inner edges of the arms 5 with a sufficient inclination to throw the inner ends or locking members 6 even with or outside of the ends of the body member 1. This necessitated shaping the sides 3 and front 2 and locating the fold lines 9 and 10 so that when the device was folded and the hooks 6 inserted in the apertures 7 there would be produced a neat closed figure having its

parts securely locked together. It will be seen that with the form developed there is a minimum amount of waste material and very little labor is required in the assembling 5 of the device. To secure the device in assembled position, it is only necessary to insert the holding members 6 in the slots 7, which is a very simple operation.

It is of course understood that the specific 10 description of structure set forth above may be departed from without departing from the spirit of my invention as set forth in this specification and the appended claims.

Having now described my invention, I 15 claim:

1. A unitary display stand comprising body, side, back and front members cut from a sheet of material, the back member having at its ends a pair of locking arms provided 20 adjacent their ends with locking fingers adapted to engage perforations in the side members so that the stand is held in assembled relation; the back member being mainly above the other members when in 25 normal operative position, and the body member being located substantially flush with the upper extremities of the front and side members.

2. A display stand of unitary construction 30 comprising a forwardly sloping body member, a downwardly inclined front member connected to the forward edge of the body member, an upwardly extending back member connected to the rearward edge of the 35 body member, and sloping sides, connected at their forward ends to the ends of the front member and inclined downwardly and laterally from the end of the body member, said side members having adjacent their 40 rearward ends apertures for the reception of locking fingers, the lateral ends of the back member having downwardly extending arms provided adjacent their ends with fingers adapted to enter the apertures in the 45 side members to hold the parts in assembled relation.

3. In a structure of the character described, a body member having an aperture for the reception of articles to be displayed, 50 a forwardly and downwardly inclined front member integrally connected with the forward edge of the body member, an upwardly extending back member integrally connected with the rearward edge of the body member, 55 rearwardly extending laterally inclined sides connected at their forward ends to the laterally inclined ends of the front member, said sides being provided adjacent their rearward extremities with perforations for 60 the reception of locking members, locking arms at the ends of the back member, said locking arms having their inner edges inclined downwardly and laterally to correspond with the inclination of the side members, and said locking arms being provided 65

adjacent their ends with locking fingers adapted to enter the apertures in the side members.

4. A unitary blank for the formation of a display stand, said blank being formed 70 from sheet material and comprising a body member having extending rearwardly therefrom a member adapted to form an upwardly extending back for the completed stand, a member extending forwardly from the body 75 adapted to form a front for the completed stand, laterally and rearwardly directed wings connected with the ends of the said front member, there being provided along the lines of junction of the front member 80 and wings fold lines, forwardly and laterally directed, said back member being provided at its ends with forwardly directed arms having their inner edges forwardly and laterally directed from the junction points of the 85 arms, back and body members, and said arms having locking fingers adapted to co-operate with the aforesaid wings.

5. In a unitary blank for the formation of a display stand, back, body, front and side 90 members, connected along indicated fold lines, the fold lines between the back and body members and between the body and front members being substantially parallel, the fold lines between the forward ends of 95 the side members and the lateral ends of the front member inclining forwardly and laterally so that when the side members are folded with respect to the front member they will incline laterally and downwardly 100 from the body member, the side members being provided with perforations and the back with fingers to co-operate with the said perforations to hold the stand in assembled relation when assembled.

6. In a unitary blank for the formation of a display stand, back, body, front and side members, connected along indicated fold lines, the fold lines between the back and body members and between the body and front members being substantially parallel, the fold lines between the forward ends of 110 the side members and the lateral ends of the front members inclining forwardly and laterally so that when the side members are 115 folded with respect to the front member they will incline laterally and downwardly from the body member, said back member having at its lateral ends integrally formed, forwardly extending arms whose inner edges 120 incline forwardly and laterally and are provided adjacent their forward ends with inwardly extending fingers.

7. An integral blank for a display stand, comprising body and back members, the 125 back member having at its lateral ends forwardly extending arms provided with inwardly extending fingers cut from the material without cutting into the body member, and side members perforated for the recep- 130

tion of the fingers when the blank is made into a stand.

8. An integral blank for a display stand, comprising body and back members, the back member having at its lateral ends forwardly extending arms provided with inwardly extending fingers cut from the material without cutting into the body member, the inner edges of the arms extending for-

wardly and laterally from the ends of the junction line between the back and body members, in combination with side members perforated for the reception of the fingers when the blank is made into a stand.

In witness whereof, I hereunto subscribe my name to this specification.

CHARLES B. KELLOGG.
